United States Patent Office

Des. 176,959
Patented Feb. 21, 1956

176,959

COIN BANK

Raymond Lesiowski, Columbus, Ohio

Application October 28, 1954, Serial No. 32,861

Term of patent 3½ years

(Cl. D34—11)

Pig. 1

Pig. 2

Pig. 3

The dominant features of my new design are shown in solid lines in the drawing.

I claim:

The ornamental design for a coin bank, substantially as shown and described.
